LACE FABRIC OR SIMILAR ARTICLE

Roger Klauber, Great Neck, N.Y.

Application September 21, 1959, Serial No. 57,623

Term of patent 14 years

(Cl. D47—6)

Fig. 1.

Fig. 2.

Fig. 1 is a top plan view of a lace fabric or similar article, showing my new design which is repeated in the vertical and horizontal directions; and

Fig. 2 is a fragmentary view showing a portion within the dotted lines in Fig. 1, enlarged.

I claim:

The ornamental design for a lace fabric or similar article, substantially as shown and described.
